TABLE

Irving M. Rosen, White Plains, N.Y., assignor to The Pace Collection, Inc., New York, N.Y.

Filed Sept. 7, 1972, Ser. No. 286,867

Term of patent 14 years

Int. Cl. D6—03

U.S. Cl. D6—175

FIG. 1

FIG. 2

FIG. 3

FIG. 4

FIG. 1 is a perspective view of a table showing my new design;

FIG. 2 is a side elevational view, the opposite side being identical;

FIG. 3 is a top plan view;

FIG. 4 is a front elevational view, the rear elevational view being identical.

The characteristic feature of my design resides in the combination of the recessed portions of the table and the corner and bottom collars as shown.

I claim:

The ornamental design for a table, as shown and described.
